AUTOMATIC TELEPHONE SYSTEM

Original Filed Nov. 14, 1930

UNITED STATES PATENT OFFICE

JOHN I. BELLAMY, OF BROOKFIELD, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

AUTOMATIC TELEPHONE SYSTEM

Application filed November 14, 1930, Serial No. 495,591. Renewed March 7, 1932.

This invention relates to automatic telephone systems in general, and more particularly to holding arrangements for use at the outgoing end of inter-office trunk lines which 5 are of sufficiently low resistance so that impulse repeaters are not required.

Heretofore, on trunk lines of the above type, it has been the practice to omit the third, or holding, conductor and to provide 10 a holding device, commonly called a series or holding repeater, comprising a low resistance relay in one conductor of the trunk line. This relay is made slow acting and furnishes a holding potential to hold the preceding 15 switches operated, or it may in turn control a slow-acting relay which furnishes the holding potential. Holding repeaters of this type are objectionable in that they increase the resistance of the trunk line and unbalance 20 the impedance of the two conductors of the trunk line, thereby decreasing the quality of impulse and voice transmission.

When the current flow over a trunk line is discontinued after its seizure and before the 25 connection is to be released, the series holding circuit will not function, as it depends upon the continued current flow to hold it up. The current flow is discontinued during conversation in toll service trunk lines used 30 in automatic telephone systems to extend connections from the toll board to the exchange in which the called line terminates. Such a toll service trunking system is disclosed in the patent to Wicks, 1,643,797, 35 granted September 27, 1927. When the toll service trunking system is laid out so that incoming toll calls must be completed from the toll board to one or more exchanges by way of automatic switches located in an intermediate or tandem exchange, a third or 40 holding conductor is employed in the trunk lines extending from the tandem exchange to the called exchange to hold the switches in the tandem exchange, because a series holding device will not function during conversation when there is no current flowing in the trunk line.

The main object of the present invention, therefore, is the provision of an improved 45 holding arrangement which eliminates the

series relay and does not affect the quality of impulse and voice transmission over the trunk line and which, moreover may be used in trunk lines wherein series holding devices will not function because of the discontinuation of the current flow at some stage of the connection. 55

The above object is attained in the present invention by bridging the grid-filament circuit of a vacuum tube across the two conductors of an outgoing trunk line and providing relays, controlled by the vacuum tube, which furnish the holding potential to the preceding switches from the time the trunk line is taken for use until it is freed, at which 60 time the holding potential is removed responsive to the full potential of the exchange 65 being impressed upon the grid-filament circuit of the vacuum tube.

A clear understanding of the method of 70 carrying out the above object may best be had from the following detailed specification when read in connection with the accompanying drawing, which shows by means of the usual schematic diagram a preferred embodiment of the invention. 75

In the drawing, the selector S is of the well known Strowger switch type having a directive vertical movement and an automatic rotary movement. The selector S may be 80 accessible to other local selectors in the same exchange, to incoming selectors terminating trunks from other exchanges in cases where the exchange in which the selector S is located is used as a tandem exchange, or directly to 85 subscribers' lineswitches. The selector S has access to outgoing trunk lines extending to different exchanges, such as the trunk line comprising conductors 76 and 77 which terminates in an incoming selector IS at a distant exchange. The incoming selector IS is preferably of the same type and may be similar to the selector S shown in full. The holding trunk HT associated with the trunk line is the holding arrangement of the present invention, and serves to furnish a holding potential to hold the selector S and other preceding switches operated. 90 95

Having described in general the apparatus shown in the drawing, a detailed explanation 100

of the operation of the same will now be given. It will be assumed that the selector S has been seized by another local selector or by a subscriber's lineswitch and that the calling subscriber desires to extend a connection to the exchange in which the incoming selector IS is located. As soon as the selector S is seized over bank contacts 1, 2, and 3, line relay 5 operates over the calling subscriber's loop and at armature 6 and its front contact completes a circuit for release relay 10 extending from ground, armature 28 and its resting contact, armature 6 and its working contact, winding of release relay 10, to battery. Relay 10 operates and at armature 11 and its working contact places ground on the release trunk conductor to hold the preceding switches in operated position. At armature 12 and its resting contact it opens a point in the release circuit of the switch and at the working contact of this armature it prepares an impulsive circuit to the vertical magnet. The calling subscriber now proceeds to dial the office designation of the desired exchange accessible over trunk lines, such as that comprising conductors 76 and 77. Responsive to the dialling of the office digit, line relay 5 releases a corresponding number of times and each time it deenergizes it closes a circuit from ground, armature 28 and its resting contact, armature 6 and its resting contact, armature 12 and its working contact, winding of series relay 15, winding of vertical magnet 32 to battery. Series relay 15 operates in series with the vertical magnet and remains operated throughout the series of impulses. The vertical magnet energizes at each impulse and raises the switch shaft and wipers of the selector to a point opposite the level in which the trunk lines to the desired exchange are accessible. At the first vertical step of the shaft, vertical off-normal springs 31 and 35 are closed. At vertical off-normal springs 31 a point is closed in the release circuit of the switch. At vertical off-normal springs 35 a circuit is prepared for the stepping relay 20, which is completed as soon as the series relay 15 operates at the first impulse transmitted to the vertical magnet. The circuit for relay 20 extends from ground, working contact of armature 11 and said armature, armature 16 and its working contact, vertical off-normal springs 35, interrupter springs 34 of the rotary magnet, winding of relay 20 to battery. Relay 20 operates in this circuit and at armature 21 and its working contact completes a locking circuit for itself independent of the contacts on the series relay 15, and at armature 22 and its working contact prepares a circuit for the rotary magnet 33.

When the series relay 15 deenergizes at the end of the train of impulses, a circuit is closed for the rotary magnet 33 extending

from ground, working contact of armature 11 and said armature, armature 16 and its resting contact, armature 22 and its working contact, winding of rotary magnet 33 to battery. The rotary magnet energizes in this circuit and steps the shaft and wipers of the selector switch onto the first set of contacts in the selected level. When the rotary magnet 33 energizes it opens its interrupter springs 34 thereby opening the circuit of stepping relay 20 and allowing this relay to release and at armature 22 and its working contact open the circuit of the rotary magnet. The rotary magnet releases and closes its interrupter springs 34 thereby again preparing a circuit for the stepping relay 20.

The operation now depends upon whether or not the trunk line accessible in the first set of contacts in the selected level is busy. If this trunk line is busy there will be ground potential present on the bank contact engaged by wiper 37 and this ground potential shunts the switching relay 25 and again completes the circuit of the stepping relay 20 over armature 29 and its resting contact, vertical off-normal springs 35, interrupter springs 34 of the rotary magnet 33, winding of stepping relay 20 to battery. Relay 20 energizes and at armature 22 and its working contact again completes the circuit to the rotary magnet, and the above operations are again repeated.

The selector switch is rotated in the above manner until the wipers encounter an idle trunk line. It will be assumed that the trunk line comprising conductors 76 and 77 and accessible to the selector switch over bank contacts 39, 40, and 41 is idle. When the wipers of the selector switch are moved into engagement with these bank contacts, wiper 37 does not encounter ground potential and the switching relay 25 is no longer short-circuited. As soon as the rotary magnet 33 deenergizes and closes its interrupter springs 34 a circuit is completed for switching relay 25 extending from ground at the working contact of armature 11 and said armature, winding of switching relay 25, vertical off-normal springs 35, rotary interrupter springs 34, winding of relay 20 to battery. Relay 25 operates in this circuit but due to the high resistance of this relay, the relay 20 will not operate in series. At armature 28 and its resting contact, relay 25 removes ground from the armature of the line relay 5 in order to prevent the release of the switch when the line and release relays deenergize. At armatures 26 and 27 and their resting contacts, the line relay 5 is disconnected and at the working contacts of these armatures the calling subscriber's loop is extended over wipers 36 and 38 and bank contacts 39 and 41 to the trunk line extending to the desired exchange. At armature 29 and its working contact the release trunk is extended to the

holding trunk HT over wiper 37 and bank contact 40.

Relay 5 deenergizes due to its disconnection from the calling loop at armatures 26 and 27, and at armature 6 and its working contact opens a point in the circuit of release relay 10 and at its resting contact closes a point in the circuit of release magnet 30. Release relay 10 is slow-to-release and maintains its armature in operated position for an interval after its circuit is opened. When this relay finally releases it removes ground from the release trunk conductor at armature 11 but this ground has been replaced by ground from the holding trunk HT, as will be explained hereinafter. At armature 12 and its resting contact, relay 10 completes a further point in the circuit of release magnet 30.

The extension of the calling subscriber's loop over wipers 36 and 38 and bank contacts 39 and 41 operates the line relay 80 of the incoming selector IS in the called exchange. At the same time the ground potential extended over wiper 37 and bank contact 40 operates relay 50 of the holding trunk HT. At armature 51 and its working contact, relay 50 closes the filament circuit of the vacuum tube 70 connecting a portion of the secondary winding of transformer 60 to the filament of this tube. The filament and plate currents for vacuum tube 70 are supplied through the transformer 60 from an alternating current source over conductors 58 and 59.

Normally with no connection to the trunk line over bank contacts 39 and 41, the full potential of the exchange battery at the distant exchange is impressed on the trunk conductor 76. The voltage of biasing battery 71 is about one-half of the voltage of the exchange battery and the negative potential on conductor 76 normally neutralizes the effect of battery 71 and maintains a negative potential on the grid of tube 70. However, when the trunk line is seized by a selector and the trunk conductors 76 and 77 are connected together over the calling loop, the negative potential at point 78 is decreased due to the voltage drop in the upper winding of line relay 80 at the called exchange, and due to the voltage drop in conductor 76 of the trunk line. The difference in the potential between points 78 and 79 with the calling loop closed is therefore somewhat less than the potential of the biasing battery 71, and this battery therefore places a positive potential on the grid of tube 70. With the filament circuit of tube 70 closed, as previously explained, and a positive potential on the grid of this tube, a plate current flows from the plate of tube 70, winding of relay 65 and the resistance 67 in parallel, secondary winding of transformer 60, to the filament of the tube. This plate current operates the relay 65 which at armature 66 and its working contact

connects ground to the winding of relay 55 to operate this relay. Relay 55 at armature 56 and its working contact connects ground to the release trunk conductor, which serves to lock the relay 50 in operated position and this ground is also returned over bank contact 40 and wiper 37 to the release trunk conductor in the selector S to hold the relay 25 of selector S in operated position before release relay 10 of the selector has had time to deenergize.

As long as the calling loop remains closed, a positive potential is maintained on the grid of tube 70 and the relays 65, 55, and 50 are maintained in their operated positions. Relay 55 maintains ground on the release trunk conductor to hold all the preceding switches in operated position. Each time the calling loop is opened during the subsequent dialling of the digits in the called telephone number, a negative potential is momentarily placed on the grid of tube 70, thereby stopping the flow of plate current through the plate relay 65. Plate relay 65 is made slow-to-release by the resistance 67 in multiple with its winding so that it will not release during the negative half cycles of the alternating current in the secondary transformer 60, and this slow-release feature also tends to keep the relay operated during the subsequent impulsing. However the relay may not be sufficiently slow-acting to hold up during the dialling of subsequent digits and the relay 55 is therefore provided with a resistance 57 in multiple with its winding so that this relay is also made slow-to-release. If relay 65 deenergizes during impulsing it opens the circuit of relay 55 momentarily, but since this relay is also slow-to-release it will not open its contacts during the momentary interruption of this circuit. The two slow-to-release relays positively insure that ground will not be removed from the release trunk conductor during the operation of the switches in the called exchange.

When the calling subscriber hangs up his receiver at the end of the conversation, the calling loop is opened and the full negative potential of the exchange battery in the called exchange is again impressed on the trunk line conductor 76. This negative potential overcomes the effect of the biasing battery 71 and the grid of tube 70 becomes negative with respect to the filament, thereby stopping the flow of plate current through the plate relay 65. Relay 65 accordingly releases, and at armature 66 and its working contact opens the circuit of the slow-to-release relay 55. After an interval relay 55 releases and at armature 56 and its working contact opens the circuit of relay 50 and removes ground from the release trunk conductor to allow the selector S to release. Relay 50 upon deenergizing, at armature 51 and its working contact opens the filament circuit

of the tube 70. The apparatus in the holding trunk HT has now been restored to normal.

When ground is removed from bank contact 40 by the release of relay 55, switching relay 25 in the selector S releases and at armatures 26 and 27 again connects the line relay 5 to the incoming line conductors. At armature 29 and its resting contact it again completes the testing circuit to the stepping relay 20 and at armature 28 and its resting contact it completes the release circuit of the selector extending from ground, armature 28 and its resting contact, armature 6 and its resting contact, armature 12 and its resting contact, vertical off-normal springs 31, winding of release magnet 30 to battery. The release magnet 30 operates in this circuit and restores the switch to its normal position. When the switch reaches its normal position the vertical off-normal springs 31 and 35 are again opened, the circuit of the release magnet being opened at vertical off-normal springs 31. The removal of ground from the release trunk conductor by the release of relay 55 also brings about the release of the preceding switches in the same manner as explained with reference to selector S.

In order to prevent any noise or hum from the alternating current source due to the capacity effect between the two windings of transformer 60 from reaching the trunk line and interfering with the voice transmission, a high resistance 75 is inserted between the connection of trunk conductor 77 to the filament of tube 70. This resistance may be as high as one megohm and serves to prevent any noise from reaching the trunk lines and also to prevent any unbalancing of the trunk lines. A switch 72 is provided to connect the filament of tube 70 either to conductor 77 through resistance 75 or to connect the filament of the tube directly to ground when the switch is operated to contact 74. In case the difference in ground potentials between the two exchanges is negligible the filament of tube 70 may be connected directly to ground and in this case a common transformer, such as 60, may be used for all of the holding trunk circuits in the exchange. In this case the vacuum tube 70 is controlled over conductor 76 with a ground return circuit, instead of over both conductors 76 and 77. Also the potential of the biasing battery 71 is preferably increased to about three-fourths of the voltage of the exchange battery, as only half the change formerly produced in the grid-filament voltage is now produced when the trunk line is taken for use.

From the foregoing, it is seen that the invention comprises a holding device which eliminates the third, or holding, conductor of inter-office trunk lines; which does not require any series relay or other resistance element in the talking conductors of the trunk line; and which is especially applicable to a

system in which the current flow over the trunk line is discontinued at some stage of the connection, since the device is not dependent on current flow in the trunk line but is rendered operative as soon as the trunk line is seized and can be released only by the application of the full normal potential of the exchange battery to the conductors of the trunk line.

What is claimed is:

1. In a telephone system, a trunk line, a vacuum tube having its grid-filament circuit bridged across said trunk line, automatic switches for extending a calling subscriber's line to said trunk line, means responsive to said extension for rendering said tube operative, and means controlled by said tube for maintaining said automatic switches operated.

2. In a telephone system, a trunk line, a vacuum tube having its grid-filament circuit bridged across said trunk line, automatic switches for extending a calling line to said trunk, means responsive to said extension for rendering said tube operative, means controlled by said tube for maintaining said switches operated, and means responsive to the opening of the calling loop for again rendering said tube inoperative thereby allowing said switches to release.

3. In a telephone system, a two conductor trunk line, a selector switch, means for operating said selector switch to seize said trunk line, means including a vacuum tube responsive to said seizure for returning a holding potential to said selector to hold the switch operated, and means responsive to the opening of the calling loop for removing said potential to allow said selector to release.

4. In a telephone system, a trunk line, a selector switch having access thereto, a test wiper in said switch, a vacuum tube associated with said trunk line, means for operating said switch to seize said trunk line, means controlled over said test wiper for rendering said tube operative, and means controlled by said tube for maintaining said last means and said switch operated.

5. In a telephone system, a two conductor trunk line connecting a first and a second exchange and terminating in a battery in the second exchange, a vacuum tube in the first exchange having its grid circuit connected to the negative conductor of said trunk line whereby said grid is normally at a negative potential to render said tube inoperative, means for extending a calling loop to said trunk line, and means responsive to said extension for reducing the effect of said battery to render said tube operative.

6. In a telephone system, a two conductor trunk line connecting two exchanges and terminating in the second exchange in a battery, a vacuum tube in the first exchange having its grid circuit connected to the negative con-

ductor of said trunk line whereby said grid is normally at a negative potential to maintain said tube inoperative, a biasing battery in said grid circuit having its positive pole 5 connected to said grid, said battery being normally rendered ineffective by said exchange battery, means for extending a calling line to said trunk line, and means responsive to said extension for rendering said tube operative, 10 the effective potential of said exchange battery being reduced to allow said biasing battery to place a positive potential on said grid.

7. In a telephone system, a trunk line connecting a first and a second exchange and terminating in a battery in the second exchange, a vacuum tube in the first exchange having its grid circuit connected to the negative conductor of said trunk line whereby said tube is normally rendered inoperative, 15 means for extending a calling line to said trunk line, a biasing battery effective responsive to said extension for rendering said tube operative, and means controlled by said tube for maintaining said extending means operated.

8. In a telephone system, a trunk line connecting a first and a second exchange, a vacuum tube in the first exchange having its grid circuit connected to the negative conductor 30 of said trunk line, means for extending a calling loop to said trunk line, a biasing battery effective when the calling loop is closed to render said tube operative, an exchange battery connected to said trunk line in the second exchange and effective to render said tube inoperative when the calling loop is opened, and 35 means controlled by said tube for supplying a holding potential to maintain said extending means operated while the calling loop is closed and for removing said potential to allow said extending means to release when the calling loop is opened.

9. In a telephone system, a trunk, an automatic switch having access thereto, a vacuum 45 tube in said trunk rendered operative by current flow over the trunk when it is seized by said switch, means controlled by said tube for supplying holding potential to said switch, and means for maintaining said tube and holding means operative independent of 50 current flow over said trunk.

10. In a telephone system, a trunk terminating in a battery, an automatic switch having access to said trunk, means in said 55 trunk for supplying holding potential to said switch, and a vacuum tube for operating said means responsive to current flow over the trunk when it is seized by said switch, said tube thereafter maintaining said means operated independent of current flow over said trunk until the full potential of said battery is applied to said trunk.

11. In a telephone system, a trunk terminating in a battery, an automatic switch having 60 access to said trunk, means in said trunk

for supplying holding potential to said switch responsive to current flow over the trunk when it is seized by said switch, and means for maintaining said holding means operated independent of current flow over said trunk, said means being rendered ineffective only when the full battery potential is applied to said trunk. 70

12. In a telephone system in which automatic switches are employed to establish a telephone connection over a trunk line and in which all battery connections are removed from the trunk during conversation, a holding circuit in said trunk, means responsive to current flow over the trunk when a connection is established thereto for rendering said holding circuit effective to supply holding potential to the switches used to establish the connection, and means for maintaining said holding circuit operative during conversation. 75

13. In a telephone system in which automatic switches are employed to establish a telephone connection over a trunk line and in which all battery connections are removed from the trunk line during conversation, means including a vacuum tube responsive to current flow over said trunk line when the same is seized for supplying holding potential to said switches, said means remaining operative when the battery connections are removed from said trunk line and releasing to discontinue the supply of holding potential only when the battery connections are again completed to said trunk line at the end of the conversation. 80

14. In a telephone system, a trunk, automatic switches for establishing a connection to said trunk, a holding circuit for said switches completed when the trunk is connected with, a battery, and means responsive to the application of the full battery potential to said trunk for opening said holding circuit to release said switches. 85

15. In a telephone system, a trunk, a battery normally connected to the conductors of said trunk, automatic switches for establishing a connection to said trunk, the battery potential on the conductors of said trunk being reduced when the connection is established thereto, and means responsive to the reapplication of full battery potential to the conductors of said trunk for releasing said automatic switches. 90

16. In combination, a control device, two talking conductors and a control conductor incoming to said device, means for establishing a connection to said device over said three conductors, a vacuum tube connected to said talking conductors, means controlled by said tube for controlling said connection over said control conductor, and means controlled over said control conductor when said device is connected with for rendering said tube operative. 110

17. In a telephone system, a trunk, means for establishing a connection to said trunk, a vacuum tube having its grid-filament circuit bridged across the talking conductors of said trunk, means controlled by said tube for controlling said connection, and a high resistance connected between the filament circuit of the tube and one talking conductor of said trunk to prevent unbalance of said trunk and interference with conversation over said trunk.

18. In a telephone system, a trunk, means for establishing a connection to said trunk, a holding circuit in said trunk including a vacuum tube having its grid coupled to one talking conductor and its cathode coupled to the other talking conductor, and a high resistance connected between said other talking conductor and the coupling to said cathode to prevent unbalance between said talking conductors and interference with conversation over said trunk.

19. In a telephone system, a trunk terminating in a battery, a holding circuit in said trunk including a vacuum tube, means for establishing a connection to said trunk, a branch circuit from one conductor of said trunk to the grid of said tube, and a battery in said branch for rendering said tube operative when the potential on said one conductor is reduced responsive to the establishment of said connection.

20. In a telephone system, a trunk line comprising two talking conductors, an automatic switch, means for operating said switch to connect with said trunk line, and means bridged across the two conductors of said trunk line for controlling the supply of holding potential to said switch, said means neither supplying current to nor drawing current from the conductors of said trunk line.

21. In a telephone system, a two conductor trunk line, an automatic switch for establishing a connection to said trunk line, and a holding device in said trunk line for supplying holding potential to said automatic switch, the sole connections of said devices to said trunk line comprising a non-conductive bridge connected across the two conductors of said trunk line.

22. In a telephone system, a trunk comprising two talking conductors, an automatic switch for establishing a connection to said trunk, a holding device in said trunk, a third conductor extending back from said holding device to said automatic switch, and means in said device exclusive of any current consuming connections to the talking conductors of said trunk for supplying holding potential to said switch.

23. In a telephone system, a trunk line comprising two metallic talking conductors extending from the banks of an automatic switch to a succeeding switch, holding equip-

ment for the first switch individual to said trunk line, a third conductor extending back to said first switch from said equipment, a non-conductive bridge across the two talking conductors included in said equipment, and means in said bridge for controlling the application of holding potential to said third conductor.

24. In a telephone system, a trunk line comprising two metallic talking conductors extending from the banks of an automatic switch to a succeeding switch, holding equipment for the first switch individual to said trunk line, a third conductor extending back to said first switch from said equipment, a vacuum tube included in said equipment and having its grid-filament circuit bridged across said trunk line, and means controlled by said tube for controlling the application of holding potential to said third conductor.

25. In combination, a trunk line extending to an automatic switch, means including a second switch for extending a connection to said trunk line, means in the first switch for supplying current over the trunk line to a point ahead of said second switch, and a potential operated device connected to said trunk line between said switches and responsive solely to potential changes on the trunk line which result from changes in the amount of current flowing from said first switch to said point for controlling the release of said second switch.

26. In a telephone system, a trunk line comprising two talking conductors extending exclusive of any series inductive windings or conductive bridges from the banks of an automatic switch to a succeeding switch, a holding device individual to said trunk, a third conductor extending from said device back to said first switch, means for supplying current over the two talking conductors from the second switch through the first switch to a calling bridge, and a potential operated device in said holding device responsive solely to changes in potential on one of said conductors which result from changes in current flow in the calling bridge for controlling the application of holding potential to said third conductor.

27. In a telephone system, a trunk line comprising two talking conductors extending exclusive of any series inductive windings or conductive bridges from the banks of an automatic switch to a succeeding switch, a holding device individual to said trunk, a third conductor extending from said device back to said first switch, means for supplying current to the talking conductors of said trunk line from the second switch, and means in said device responsive to a potential in one of said talking conductors for controlling the application of holding potential to said third conductor.

28. In a telephone system, a trunk line

comprising two talking conductors extending exclusive of any series inductive windings or conductive bridges from the banks of an automatic switch to a succeeding switch,
5 a holding device individual to said trunk, a third conductor extending from said device back to said first switch, and means including a vacuum tube in said device having its grid connected to one talking conductor for controlling the application of holding potential to said third conductor.

In witness whereof, I hereunto subscribe my name this 8th day of November, A. D. 1930.
